UNITED STATES PATENT OFFICE

2,672,633

GOLF BALL CLEANER

Louis S. Allen, Alexandria, Va.

Application April 15, 1947, Serial No. 741,607

1 Claim. (Cl. 15—21)

1 This invention relates generally to devices for cleaning golf balls and, more particularly, to such a device which is constructed and adapted to be mounted on a golf club bag whereby it may be carried with the player for use at any time.

Portable golf ball cleaners have heretofore been proposed and various devices of this type are known. None of these, however, has combined the desirable features of lightness of weight and ease of operation with the good cleaning and polishing action of the so-called fixed ball cleaners which are usually permanently located at the tee. The provision of a portable cleaning device embodying the combination of these desirable features has therefore been one of the principal objects of this invention. Another object of the invention has been to provide a portable ball cleaner having moving cleaning means, together with other means for positively holding the ball against movement with the cleaning means while the same is being operated. A still further object of the invention has been to provide a ball cleaner including a sponge for transferring water to the ball while it is being cleaned and including also a reservoir for water or other cleaning fluid which may be used to wet the sponge whereby the cleaning device may be used for relatively long periods of time without the necessity of periodically wetting the sponge at some fixed source of water or cleaning fluid. A still further object of the invention has been to provide a device of the described type which is susceptible of cheap and easy manufacture, is light in weight and simple in operation, and may be manufactured from attractive and readily-available materials such as the synthetic plastics.

Other objects and features of novelty of the invention will be made apparent by the following description and the annexed drawings which, it will be understood, are only illustrative of the invention and impose no limitations thereon not imposed by the appended claim.

Referring to the drawings, in which similar reference numerals refer to like parts,

Fig. 1 is an elevational view of a form of golf ball cleaning device according to this invention;

Fig. 2 is a sectional view taken on line 2—2 of Fig. 1;

Fig. 3 is a sectional view, similar to Fig. 2, but showing a modified form of the invention, and

Fig. 4 is an elevational view, partly in section, of another, preferred form of the invention.

In Figs. 1 and 2 of the drawings, I have disclosed, as one embodiment of the invention, a golf ball cleaning device adapted to be attached to a

2 golf club bag 2 whereby it may be carried with the player at all times. This device comprises a body member 4 at one end of which is connected an L-shaped arm 6, the longer leg of which extends in spaced parallel relation to the straight end wall 8 of the body part, forming a recess within which the upper edge of the annular wall of a golf bag may be inserted. A screw 10 is threaded through the arm 6 in the direction of the body 4 and may be turned to clamp the cleaning device firmly to the golf bag. A ring 3 is preferably integrally attached to the body and provides a means for attaching a rag or towel to the ball cleaner. The body member 4 is formed with a cylindrical opening 20 extending entirely therethrough and within this opening there is rotatably journaled a cup-shaped member 22 having a cylindrical wall 24 and a bottom 26, the other end being open. The outer surface of the cylindrical wall 24 of this cleaning cup is stepped as at 28 to inter-engage with an inwardly-extending flange 30 on the inner wall of the opening 20 in order to prevent removal of the cup-shaped member from the opening 20 in one direction. A retaining ring 32 may be positioned within the opening 20 above the cylindrical wall 24 in order to prevent removal of the cup-shaped member in the other direction. An operating handle 34 is eccentrically connected to the bottom 26 and extends outwardly therefrom to provide a means of rotating the cleaning cup. Within the cleaning cup the surface of the cylindrical wall 24 is substantially covered by brush means, such as the bristles 40, which are attached at their one ends to the cylindrical wall 24 and extend radially inwardly therefrom, forming a rotatable annular ring of bristles. Also within the cleaning cup and substantially covering the bottom wall thereof is a sponge member 42, which is preferably removable and replaceable and which may also be impregnated with a cleaning material, such as soap, which becomes active when the sponge is wetted.

In the use and operation of the described device, a golf ball A is inserted into the cleaning cup in the manner shown in Fig. 2 and is pressed against the sponge 42 which is in the bottom of the cup. In this position the bristles 40 will tightly engage the outer surface of the ball and if the cleaning cup is now rotated by manipulation of the handle 34, while the ball is held from rotation, the bristles will rub the outer surface of the ball and clean the same. Pressure of the ball against the sponge will cause water or cleaning fluid therefrom to flow over the outer surface

of the ball to assist the cleaning action of the bristles. By rotating the ball to various positions within the cup, the entire outer surface thereof may be cleaned.

In Fig. 3 of the drawings there is disclosed a modified form of the invention in which the ball is held within the cup by mechanical means and the cup is completely closed while the cleaning operation is being performed. This embodiment of the invention is identical in structure with that of Figs. 1 and 2 but in addition is provided with a cover 50 pivoted to the body 4 of the cleaning device by hinge 52. The cover 50 is of such size and shape that it completely covers the open end of the cleaning cup when in its closed position. At a part of the cover opposite the hinge 52 there is provided a latch means 54 whereby the cover may be retained in closed position. Attached to the inner surface of the cover there is a plurality, preferably 4, of spring fingers 56 which extend toward and into the interior of the cleaning cup in such a way that a ball may be positioned between them and will be tightly held by them when it is in cleaning position within the cleaning cup.

In the use and operation of the device of Fig. 3, the cover 50 is first opened and a golf ball is placed in position between the spring fingers 56. The cover is now closed, forcing the ball into the cleaning cup and within the annular ring of bristles 40 and against the sponge 42. When the cleaning cup is rotated by the handle 34, the golf ball will be held against rotation by the spring fingers 56 and will be cleaned in the manner described hereinbefore.

In the preferred embodiment of the invention which is disclosed in Fig. 4 of the drawings, the body of the cleaning device is formed to provide a reservoir for water or other cleaning fluid, which communicates with the cleaning cup adjacent the location of the sponge therein, whereby the sponge may be replenished from time to time with the cleaning fluid within the reservoir. As disclosed in Fig. 4, the body 4 of the cleaning device is provided with a preferably cylindrical chamber 60 which is closed at its outer end by a screw cap 62. A passage 64 leads from this chamber to the cleaning cup 22 at a part thereof adjacent the sponge 42. The wall 24 of the cleaning cup has an opening 66 therethrough which, in one position of the cleaning cup, registers with the passage 64 to permit the liquid within reservoir 60 to flow through the passage 64 and the opening 66 to the sponge 42 to moisten the same. In all other positions of the cleaning cup, the wall 24 thereof prevents the flow of liquid from the reservoir and passage 64 to the sponge.

On the outside of all cleaners according to the invention there may be provided an auxiliary cleaning pad for the purpose of removing stains which are not removable by the brush means 40. Such a pad is shown at 70 in Fig. 1 and comprises a flat member fixed to an outer face of the body

4 and having cleaning means such as stiff bristles extending outwardly therefrom and against which the ball may be rubbed.

While I have described and illustrated a number of embodiments of my invention, it will be apparent to those skilled in the art that other embodiments, as well as modifications of those disclosed, may be made without departing in any way from the spirit or scope of the invention, for the limits of which reference must be made to the appended claim.

What is claimed is:

A portable golf ball cleaning device comprising a body of such size and weight that it is adapted to be supported on a golf bag and having a generally cylindrical opening entirely therethrough, a cup-shaped member having a side wall rotatably journaled in said opening and having a bottom accessible through one end of the opening and an open end accessible through the other, cleaning means lining the interior of the bottom and side wall of the cup-shaped member and forming a ball-receiving recess slightly less in diameter than a golf ball into which a golf ball is adapted to be forced and within which it may be held fixed during the cleaning operation, the said body having a chamber formed therein which is spaced from the opening extending therethrough and which has a stoppered exterior opening and is adapted to contain a cleaning liquid, said body also having a passage therethrough communicating said chamber to said cylindrical opening, the said cup-shaped member having an opening in the side wall thereof which is positioned to periodically register with said passage during rotation of the cup-shaped member to cause cleaning liquid to flow from the chamber to the interior of the cup-shaped member, and a handle attached to the bottom of the cup-shaped device and extending exteriorly of the body for rotating the cup-shaped member.
